UNITED STATES PATENT OFFICE.

BENJAMIN R. JOLLY, OF RALEIGH, NORTH CAROLINA.

WATCH-CARRYING DEVICE.

1,165,262.

Specification of Letters Patent. Patented Dec. 21, 1915.

Application filed December 12, 1913. Serial No. 806,273.

To all whom it may concern:

Be it known that I, BENJAMIN R. JOLLY, a citizen of the United States, and residing at Raleigh, county of Wake, State of North Carolina, have invented certain new and useful Improvements in Watch-Carrying Devices, of which the following is a specification, reference being had therein to the accompanying drawing.

10 My invention relates particularly to that type of watch holding device adapted to be attached to the wrist of the wearer.

15 It has for its principal object the attainment of maximum security of position for the article held without detracting from the requisite ornamental appearance of the article or the holder.

20 It has also been my aim to enhance the ornamental design and this has been done without sacrifice of the efficiency of the device.

25 Subsidiary objects have been simplicity, lightness, adjustability and low cost of manufacture.

All of these objects have been attained.

30 Broadly speaking my watch holder comprises a base portion against which the back of a watch may be seated, upwardly extending prongs arranged to hold the watch between them and against the base, together with means for fastening the holder to the person or the wearer.

35 Speaking more specifically, my invention comprises a watch holder composed of strip material bent to form a star-shaped figure the points of which are bent upwardly and inwardly to receive and hold a watch between them and against the body portion of the figure, and strap or chain fastening 40 means connected with opposite points of the figure and comprising two connected series of parts of a two part fastener, the one series being composed of flexibly connected similar parts and the other series being composed 45 of flexibly connected complementary parts arranged to register with the aforesaid parts when the ends of the strap are over-lapped and to be fastened together.

50 Additional features there are which will appear fully from the following description and the accompanying drawings.

55 In the accompanying drawings I show only the several forms of my invention now best known to me, but I desire to have it understood at the outset that my invention may be given many forms by those skilled in

the art without departing from the spirit thereof and in the annexed claims hereto I intend to cover all such forms.

Figure 1 is a top plan view of the device 60 of my invention in extended position, Fig. 2 is an end view of the same as it would appear on the wrist of the wearer, a supported watch being shown in position, Fig. 3 is a plan view of a modification in extended 65 position, Fig. 4 is a modified form of the holder *per se*, Figs. 5 and 6 are a side elevation and plan respectively of an adjusting tool for adjusting the size of the holder to suit the size of the watch, Fig. 7 is a view 70 of still another modification in which the fastening means takes the form of a metal chain, Fig. 8 is a similar view of a still further modification, Figs. 9 and 10 illustrate 75 details of certain of the joints of Figs. 7 and 8, being sections on lines 10-10 and 11-11. Figs. 11 and 12 show two further modifications by plan view.

Like numerals refer to like parts in all 80 the figures.

The watch holder proper is designated 10, while the connected fastening means or wrist strap is designated 11.

Speaking first of the holder, and referring 85 particularly to Figs. 1, 2, 4 and 7, it will be seen that the holder is composed of resilient strip material bent or stamped of sheet-metal to form a star-shaped closed figure. This figure may also be formed of wire, there being a wide choice of material. 90 The points or corners 12 thereof are bent upwardly and inwardly from the base or body portion 13 to form spring prongs arranged to hold the watch 14 between them and against the base portion 13. The curvature 95 of the upwardly and inwardly bent prongs 12 is such that they fit accurately the edges of the average watch, and preferably the strip material is of such nature that the prongs 12 may be bent to conform to the 100 edges of any of the standard watches. Thus the material combines resiliency and pliability. Preferably the figure of the holder 10 is regular in form, and the prongs 12 are substantially diametrically opposite as 105 shown, but variation from this may be had if desired. The regular form has considerable advantage in that when strain is put upon any two substantially opposite prongs tending to draw them apart, and thereby 110 free the watch, those substantially on a diameter at right angles thereto are at the

same time drawn toward each other whereby the watch is still more tightly clamped. It is therefore practically impossible under ordinary conditions of use for accidental removal or dislodgment of the watch to take place. It is only by careful prying back of one prong at a time that the watch may be removed.

Referring more particularly to the form of Figs. 1, 2 and 3, the strip fastener 11 connected with the holder is composed of laminated flexible material. The center portion of the strap is enlarged, and between the laminations at this point the base 13 of the support 10 is laid, certain of the prongs 12 projecting up through apertures 15 in the outer lamination, while certain others project upwardly around the edges thereof. The opposite ends of the strap are sewed on the edges, and up to a point closely adjacent the support 10, the sewing being illustrated by the dotted lines along the edges and concentric with the support 10. Mounted on this strap are two series of parts of a two part fastener, one series on each side of the support 10. One series comprises similar spaced stud members 16, and the other series similar complementary socket members 17, so arranged that when the two ends of the strap are overlapped as shown in Fig. 2, the stud and socket members register and may be fastened together. The parts of the fastener in each series are equidistant from each other, whereby the two ends of the strap may be overlapped to any desired extent and the parts fastened together, thereby forming a bracelet of any desired size.

In the use of this device, after the holder 10 has been put in place as shown in Fig. 1, the strap 11 is pushed back upon one of the prongs 12 sufficiently to allow the branches of the prong to be spread apart to admit the stem 18 of the watch between them, whereupon the strap is pulled taut so that its central portion may lie flat against the base 13 of the holder 10, and the body of the watch is then carefully inserted between the prongs 12, use being preferably made of a pointed tool of some material which will not injure the watch casing, or if the prongs 12 are not extremely stiff, the fingers may be used with equal facility. With the watch in this position, after the strap has been placed around the wrist, any strain on the strap tending to draw it from the wrist puts the tension on the central portion 19 and thereby tends to draw the prongs 12 which project through apertures 15 apart, with the result that the prongs at right angles thereto hold all the tighter. So also if the watch itself is grasped at any point between the prongs and an attempt is made to move it, the greater the strain placed upon it, the tighter the prongs 12

clasp the watch. The only way in which the watch may be removed without the use of a disrupting force is by careful bending back and disengaging one prong at a time. It will be readily seen that this is something which cannot be done by accident, or in haste, but must be by deliberate act.

It is my intention to manufacture the device with the holders 10 of several different sizes, and these several sizes will fit all standard watches. Where there is variation in the size of the watch, I intend to adjust the holder 10 to size by spreading the prongs 12 or retracting the same. In Figs. 5 and 6 I show a very efficient tool which I have devised for this purpose. It comprises four angular channel bars 20 connected together at the top by solder 21 or other suitable means and extending on diverging lines to form a pyramidal figure. These channel members 20 may be integrally formed from sheet or block metal if desired, instead of being separately formed and soldered or otherwise fastened together. In order to enlarge the holder 10, the holder is forced down over the top of the tool with the inner corners 22 of the figure in the channels of the bars 20, the corners 22 being thereby bent to enlarge the figure of the holder. The same tool when applied exteriorly to the figure of the holder 10 instead of interiorly thereof, will serve to draw the corners 22 toward each other and to the center of the figure instead of to spread them apart. In this application the holder 10 is pushed down between the diverging ends of the members 20 instead of over the converging ends.

As clearly apparent, the form of Fig. 3 differs from Fig. 1 in that the complementary parts 17 of the fasteners are in the form of button holes instead of button caps, the buttons 16 in this modification being made perhaps somewhat larger than the buttons or studs 16 in Fig. 1, and shaped specially to coöperate with the button holes.

In the form of Fig. 7 the fastening device 11 comprising a chain each link of which 23 on one side of the support 10 is provided with a stud member 16 of a fastener, and each link of which on the opposite side of the member 10 is provided with a complementary socket member 17. When overlapped these stud and socket members may be fastened together precisely as in the case of Figs. 1 to 3. In order to increase the flexibility thereof I may provide lost motion connections between the links 23 as shown clearly in Fig. 10. The end link of each series of fastener parts 16, 17 is connected by a yoke 24 directly with the prong 12 of the support 10, suitable small lugs 25 being integrally formed with or attached to the prong in each case at or near its base. The support 10 is a four

pronged support, the prongs 12 of which are diametrically opposite whereby when strain is placed upon the chain fastening 11, the prongs 12 in the line of the chain are drawn apart, and the prongs at right angles thereto are drawn together. In connection with this fastener as in connection with the fasteners of Figs. 1 to 3, I provide complementary socket members 17 disassociated from the series of the connected links, and which may be placed separately upon the one or two stud members 16 which are exposed after the bracelet has been adjusted to the size desired.

The form of Fig. 8 differs from the form of Fig. 7 primarily in the form of the support 10. The strip material instead of being bent to form a closed figure in this case is bent to form an open figure, having one main prong 12 at the center of the strip and two additional prongs 12' on the opposite side thereof, formed by turning upwardly and inwardly the ends of the strip itself. These prongs 12' are preferably interconnected by a tie member 26, to lugs or pintles of which the yoke 24 is connected. Of course in so far as the tie member 26 and that portion of the figure excluding prongs 12' are concerned, the figure is still a closed figure, the tie member 26 being the connecting link. In this form also the lugs 25 on the prong 12 are clearly shown. The additional difference is in the manner of connecting the links of the chain together. In Fig. 7 each link is provided at one end with laterally spaced beads 27 in which is socketed a pin 28 passing through the ear 29 (see Fig. 10) of the adjacent link, the opposite end of each link being provided with an ear 29. But in Fig. 8 each link is provided at one end with a slotted tongue 30 and at the other end with a tongue 31 passed through the slot in the tongue 30 of the succeeding link and turned over the edge thereof as shown in Fig. 11.

Still a third form of support is shown in Fig. 4 in which there are provided 8 prongs 12 instead of 4.

Obviously the fastening means 11 of my invention is capable of use independently of the watch support 10 as a bracelet, but I do not claim the same herein as it forms the subject matter of a separate application, Serial No. 49,728, filed September 9, 1915.

I show two other modifications in my invention in Figs. 11 and 12. According to the modification of Fig. 11, the two halves of the bracelet chain of the form of Figs. 7 and 8 are attached respectively directly to the opposite sides of the casing of the watch, thus forming a bracelet watch. There are such watches on the market to-day, but none of them are equipped with the bracelet chain of my invention. Equipped with this chain, the adaptability of the device to wrists of

various sizes and shapes is increased many times. In other devices, adjustment can only be secured in a very limited way or by cumbersome means, but through the use of my invention, there is permissible a number of adjustments limited only by the number of links in the chain or the number of fasteners in the strap (if a strap be used), this adjustment being carried out in the act of fastening and additional overt act of adjustment being unnecessary in any case. The lengths of the two parts of the chain are substantially equal and each such that when fastened together about the wrist they each extend substantially entirely around the wrist of the average small size. When placed around wrists of larger sizes, they do not over-lap all the way around the wrist, but lack one or two links, upon which links are placed the extra complementary fastener members. Once placed these extra members are allowed to remain in position, so that the act of fastening is the same irrespective of whether the parts of the chain over-lap entirely around the wrist or not. These complementary members may either be furnished in sets of a certain number with each chain, or they may be furnished in varying number, according to the size specified when the purchase is made, being snapped on at the time of purchase by the jeweler.

The form of Fig. 12 shows my invention applied to the well known leather wrist strap holder. This type of holder includes a centrally disposed leather pocket P in which the watch is housed with its face exposed as is well known. The complementary halves of the strap are practically identical with those shown in Figs. 1, 2 and 3. As heretofore stated, extra complementary socket or button members are furnished with this form as well.

In concluding I desire to make it clear that the lost motion of the chain of Figs. 7 to 9, and the flexibility of the strap are equivalents in their function, both acting to insure flexibility of the bracelet formed by the over-lapping parts. In their stead equivalent means of connection between the fastener elements may be used to the same end, such for instance as spring connections.

What I claim is:

1. A holder for a watch comprising a base portion provided with upwardly and inwardly turned spring prongs adapted to hold a watch between them, said prongs being jointly and symmetrically expandible about the center of the base to fit watches of different diameters, in combination with carrying means for the holder comprising terminal elements with co-operating connecting devices and intermediate connections to opposite sides of the holder, said terminal elements, and their points of connection to the holder extending in a line passing

through the center of the base, about which the spring prongs are symmetrically arranged.

2. A watch holder composed of strip material in the form of an angular figure, the corners of which are upwardly and inwardly turned and arranged to hold a watch between them, in combination with carrying means for the holder comprising terminal elements with coöperating connecting devices and intermediate connections to opposite sides of the holder, said terminal elements, and their points of connection to the holder extending in a line passing through the center of the base, about which said corners are symmetrically arranged.

3. A watch holder composed of strip material bent to form an angular closed figure, the corners of which are turned upwardly and inwardly and arranged to hold a watch between them, in combination with carrying means for the holder comprising terminal elements with coöperating connecting devices and intermediate connections to opposite sides of the holder, said terminal elements, and their points of connection to the holder extending in a line passing through the center of the base, about which said corners are symmetrically arranged.

30 4. A watch holder composed of strip material bent to form a closed figure comprising a series of outwardly extending loops serially connected and projecting in symmetrical relation from the central portion of the figure, the outer ends of said loops being upwardly and inwardly turned to clasp and hold the watch between them.

5. A watch holder composed of strip material bent to form a symmetrical figure having serially connected radial loops, the points of which are upwardly and inwardly bent to hold the watch between them and against the body portion thereof, in combination with carrying means comprising elements secured to opposite prongs or loops of the holder, said elements carrying coöperating fastening devices and adapted when fastened together to bring a strain upon the loop member of the holder, whereby they will tend to contract upon a watch case.

55 6. A watch carrying device composed of strip material bent to form a star-shaped figure, the points of which are upwardly and inwardly bent to hold a watch between them and against the body portion of the figure, and a wrist bracelet opposite portions of which are attached to diametrically opposite up-turned points of said figure.

60 7. A watch carrying device comprising a substantially flat base portion having upwardly and inwardly bent prongs connected therewith and arranged to hold a watch between them and against the base, together with a laminated wrist strap between the laminations of which said base portion is

laid with certain of its prongs projecting through apertures in the upper lamination, whereby the back of the watch rests against the outer lamination of the strap.

8. A watch carrying device comprising a 70 base portion having upstanding prongs arranged to hold a watch between them and against said base, a laminated wrist strap between the laminations of which said base is laid with its prongs projecting through 75 apertures in the exterior laminations, and means securing the laminations together at points removed from the base portion of said holder.

9. A device of the class described comprising a watch, and two complemental series of flexible connecting fastening parts connected therewith and extending from opposite sides thereof, the series on one side being composed of fastener parts all alike, and 80 spaced apart at equal intervals, and the series on the other side consisting of corresponding complemental fastener parts so arranged that when one series is overlapped on the other, the fastener parts of the two series 85 will properly engage throughout, without respect to the length of the overlap, and thus 90 secure the watch.

10. A device of the class described comprising a watch, and two complemental series of 95 flexibly connected fastener parts connected therewith and extending from opposite sides thereof, said series being of approximately the same length, which length is substantially sufficient to extend around the 100 entire wrist when the device is in use, one of said series comprising similar fastener parts, and the other similarly spaced complemental fastener parts, whereby when overlapped the parts of the fasteners register 105 and may be snapped together.

11. A device of the class described comprising a watch, and a bracelet chain connected therewith, the links of which are formed in two connected series, one series 110 extending from each side of said watch, the links of one series comprising similar connected parts of a two part fastener and those of the other series connected complemental parts of the same, some of said links having a lost motion connection with each other, whereby when over-lapped the two series of parts register and may be fastened together to form a closed bracelet itself having 115 flexibility.

12. A watch holder composed of resilient strip material bent to form a star-shaped symmetrical figure, the points of which are upwardly and inwardly bent to hold a watch 125 between them and against the body portion thereof, each point of the figure constituting a bow spring drawing together the adjoining loops.

13. In combination, a watch holder having claw-shaped radial prongs, and a carry- 130

ing device comprising oppositely extending members secured to opposite prongs of the holder, and adapted to be overlapped and adjustably secured together at their extremities, whereby watches in holders of different sizes may be secured by the same carrying device to wrists of different circumferences.

Copies of this patent may be obtained for five cents each, by addressing the "Commissioner of Patents, Washington, D. C."

In testimony whereof I affix my signature in presence of two witnesses.
